UNITED STATES PATENT OFFICE

ELMER H. HYDE, OF PITTSBURGH, PENNSYLVANIA, ASSIGNOR TO AMERICAN TAR PRODUCTS COMPANY, INC., A CORPORATION OF DELAWARE

COMPOSITION OF MATTER

No Drawing.

Application filed May 27, 1930. Serial No. 456,293.

This invention relates to compositions of matter and a process of preparing the same and more particularly to an improved disinfectant.

5 An object of the present invention is to provide an emulsion of tar acids or tar acid oils by means of a material obtained as a by-product in the manufacture of paper in the preparation of pulp, particularly by the 10 soda or the sulphate processes. This material is generally known as "liquid resinate" or "liquid sodium resinate" and is obtained from black liquor in a form which renders it particularly suitable for use in emulsifying tar 15 acid oils.

Liquid resinate is a yellowish brown, viscous substance which varies widely in its composition and contains generally rosin acids, fatty acids, lignin, caustic materials, water, 20 and in some cases a small percentage of phytosterins. In connection with the present invention, the liquid resinate as obtained from black liquor in the treatment of coniferous woods is ready for use and requires 25 little or no further treatment. Since it has the desired alkalinity, the expense and labor of further adding alkaline materials is eliminated.

30 In preparing a disinfectant, about 70 to 75% by weight of tar acid oil containing 25% tar acids are mixed with 30 to 25% by weight of liquid resinate or enough to give a pH value of about 8. The materials may be 35 mixed by means of mechanical or air agitation in a tank equipped with steam coils. The mixture is heated to about 75° C. and is agitated until it appears homogeneous. The resulting product is filtered and is then ready 40 for use.

The following examples are given by way of illustration:

Example 1.—A disinfectant having a coefficient of 2 plus in accordance with Rideal- 45 Walker (1921 modification) may be prepared

by mixing the following ingredients in the proportions given:

	Per cent by weight
Tar acid oil (25% tar acids)	68
Liquid resinate	30
Castor oil soap	2

Example 2.—A disinfectant having a coefficient of 3 plus may be prepared by mixing the following ingredients together in the proportions given:

	Per cent by weight
Insecticide oil	56.0
High boiling tar acids	4.0
Water gas tar distillate	8.0
Liquid resinate	30.0
Castor oil soap	2.0

In the above examples, rather than adding the liquid resinate to the oily portions, it is 65 preferable to add the oily portions such as the tar acids, insecticide oil, and water gas tar distillate, to the liquid resinate while stirring and heating. The remaining ingredients may be added in any order.

70 Water is added to the above compositions to produce a disinfectant in the form of an emulsion. Any desired proportion of water may be used. The emulsion formed is of an exceptionally stable character.

75 Any animal or vegetable oil soap may be substituted for castor oil soap to aid in stabilizing emulsions. For instance soya bean oil soap or stearic acid soap may be used. Sulphonated oils may also be used.

80 Any one or a mixture of two or more tar acids may be used instead of tar acid oil as for instance phenol, cresols, their homologues or their chlorinated products or other derivatives which have bactericidal action. 85 However, a cheaper product is obtained by using tar acid oil. For the purpose of fortifying a disinfectant, high boiling tar acids such as xylenols and the higher homologues 90 may be included.

As shown in Example 2, a so-called "insecticide oil" may be added and may serve to supply the main bulk of the tar acids. Insecticide oil is a coal tar distillate which contains about 25% to 35% phenol and its homologues and from which substantially all of the material which crystallizes out upon cooling to about 5° C. is removed.

The water gas tar distillate listed above 10 may be added as a stabilizer and to lower the viscosity and the specific gravity of the finished disinfectant. This distillate is comparatively free from naphthalene and is a fraction obtained from water gas tar between 100° C. and 355° C.

15 With certain tar acids and by properly adjusting the proportions of materials used, disinfectants may be prepared having phenol co-efficients up to 25 plus.

20 By the present method, the manufacture of disinfectants from tar acids is rendered very simple. The materials may be mixed in any proportions and at room temperatures or higher. Little or no solid materials 25 are required to be dissolved or handled, and emulsification takes place readily.

I claim as my invention:

A disinfectant emulsion consisting of tar acid oil, water gas tar distillate which is 30 comparatively free from naphthalene and which is obtained as a distillate from water gas tar between 100° C. and 355° C., water, and "liquid resinate" containing rosin acids, fatty acids, lignin, caustic materials, and 35 water.

In testimony whereof, I have hereunto subscribed my name this 26th day of May, 1930.

ELMER H. HYDE.
